UNITED STATES PATENT OFFICE

169,992

SHAPED TEXTILE FABRIC

Madalyn Miller Schimmel, Los Angeles, Calif.

Application September 15, 1952, Serial No. 21,459

Term of patent 7 years

(Cl. D92—1)

To all whom it may concern:

Be it known that I, Madalyn Miller Schimmel, a citizen of the United States, residing at Los Angeles, in the county of Los Angeles and State of California, have invented a new, original, and ornamental Design for Shaped Textile Fabric, of which the following is a specification, reference being had to the accompanying drawing, forming part thereof.

In the drawing:

The figure is a plan view of a segmental panel of a shaped textile fabric, showing my new design.

I claim:

The ornamental design for a shaped textile fabric, substantially as shown.

MADALYN MILLER SCHIMMEL.
